SLACK OR CUTTINGS REMOVING DEVICE
FOR KERF-CUTTING MACHINESFrank A. Lindgren, La Grange, Ill., assignor to
Goodman Manufacturing Company, Chicago,
Ill., a corporation of Illinois

Application May 10, 1946, Serial No. 668,963

9 Claims. (Cl. 262—28)

1

This invention relates to improvements in slack or cuttings removing devices for kerf-cutting machines of the mounted type adapted to cut an arcuate kerf in a mine wall along the mine bottom, and has among other objects to provide a novel and compact form of slack removing device for a kerf-cutting machine of the class described for efficiently removing the cuttings from its cutter chain.

Devices of the screw conveyor type for removing the cuttings from the underframe of a kerf-cutting machine, to reduce the amount of cuttings carried back into the kerf by the cutter chain, have heretofore been used with shortwall machines with a great deal of success. These slack removing devices besides increasing the efficiency of the machine by taking the cuttings away from the cutter chain so they are not carried back into the kerf—also reduce the dust in the air for the reason that the cuttings are confined to the underframe of the machine and are discharged from the underframe along the ground by the screw conveyor, the pile being built up by the conveyor from its inside. With the shortwall type of cutting machine, however, the travel of the machine is fast enough to prevent the building up of the pile of coal to a height which would reduce the efficiency of the screw conveyor and place excessive loads thereon. When attempting to use this same type of slack removing device on a machine of the mounted type, which cuts an arcuate kerf by movement of the cutting element about a fixed vertical axis, the distance traveled by the rear end of the cutter chain is relatively short compared to the length of the kerf cut, with the result that the pile of slack coal becomes so high that the efficiency of the screw conveyor is reduced and the power required to drive the screw conveyor is increased to such an extent as to greatly hamper the use of slack removing devices for this type of kerf-cutting machine.

In carrying out my invention I remedy these difficulties by attaching a simple and efficient form of power driven screw conveyor to the rear end of the cutter head of a mounted type kerf-cutting machine, which opens in cuttings receiving relation with respect to the cutter chain of the machine and is arranged to confine the cuttings as they leave the kerf and to discharge the cuttings at the rear of the cutter chain to one side thereof. I also provide a pile leveling means mounted on the cutter head of the kerf-cutting machine which is arranged in the path of the cuttings discharged therefrom, to level off the pile of cuttings discharged by said screw conveyor and

2

avoid the overloading of said conveyor element that would be caused by the building up of high piles of cuttings from the inside of the pile by said screw conveyor element.

These and other objects of my invention will appear from time to time as the following specification proceeds and with reference to the accompanying drawings wherein:

Figure 1 is a fragmentary view in side elevation 10 of the front end of a mining machine of the mounted type, with certain parts thereof broken away and certain other parts shown in substantially longitudinal section;

Figure 2 is a fragmentary transverse sectional view taken through the cutter chain drive sprocket 15 of the machine shown in Figure 1;

Figure 3 is an enlarged fragmentary horizontal sectional view showing certain details of the means for leveling the pile of cuttings discharged by the screw conveyor and of the drive to the screw conveyor and the pile leveling means;

Figure 4 is a fragmentary transverse sectional view taken through the screw conveyor and pile leveling means;

Figure 5 is a fragmentary sectional view taken substantially along line 5—5 of Figure 3;

Figure 6 is a fragmentary sectional view taken substantially along line 6—6 of Figure 4;

Figure 7 is a fragmentary sectional view taken substantially along line 7—7 of Figure 3; and

Figure 8 is an end view of the cuttings removing conveyor with certain parts of the pile leveling means shown in section.

In the embodiment of my invention illustrated in the drawings, the slack removing device is shown as being applied to a kerf-cutting machine 10 of the mounted type. Said kerf-cutting machine may be of a well known construction and operation and comprises a turntable 11 mounted on a truck 12 and having a cutting element 13 mounted thereon on trunnion supports 14, 14, and projecting beyond the forward end of said truck and turntable.

The cutting element 13 has a cutter head 15 depending therefrom and vertically adjustable with respect thereto in guides 16, 16, in a manner which is usual with machines of this type. Said cutter head is of a well known construction and includes a pivoted cutter bar support 17, which 45 forms a support for a projecting cutter bar 19. Said cutter bar and support are adjustable about a vertical axis coaxial with a splined drive shaft 24 and may be locked from turning movement about said axis during the cutting operation. Pivotal adjustment of said support and cutter bar

is provided to permit the cutter bar to be positioned to extend along a rib of the working place in substantially parallel relation with respect thereto, when the machine is to one side of said rib. A cutter chain 20 is guided for orbital movement about said cutter bar and is driven from a cutter chain drive sprocket 21 mounted on a lower end of a sleeve 23 journaled in said cutter bar support. Said sleeve in turn is driven from the lower end of the splined shaft 24, which is vertically slidably in the hub of a bevel gear 25 journaled in the projecting portion of the cutting element 13, and is driven from a motor 22 at the rear end of said cutting element 13 through a gear train indicated generally by reference character 26. Said gear train may be similar to that shown in Patent No. 1,938,850, which issued to W. T. McCullough on Dec. 12, 1933, and is no part of my present invention so will not herein be shown or described in detail.

The conveying means for collecting and discharging the slack cuttings to the retreating side of the cutter bar includes a tubular casing 27 with a screw conveyor or helical screw 30 rotatably mounted therein. Said casing is secured to the rear end of said cutter head and extends at a slight angle with respect to the longitudinal center line of the cutter bar so that the discharge end of said casing is closer to the cutter chain as it turns about the drive sprocket 21 than the receiving end thereof, to position an inner open portion 31 of said casing in cuttings receiving relation with respect to said cutter chain. Said casing is provided with forward upright flanged portions 32 and 33 which are detachably secured to wall portions 34 and 35 extending transversely of said cutter head at the rear end thereof, by means of suitable cap screws and nuts and bolts.

The casing 27 is also provided with two laterally spaced arcuate forwardly projecting walls 39 and 40 extending forwardly therefrom beneath said cutter head along the advance and retreating sides of the cutter chain 20 respectively, and secured to the underside of said cutter head by means of nuts and bolts 41, 41 (see Figures 2 and 3). Said arcuate walls have upturned lower ends so they may slide along the mine bottom and confine the cuttings to the path of the cutter chain 20 as said cutter chain rounds its drive sprocket. Cuttings guide shields 42 and 43 extend forwardly of the forward ends of said arcuate walls 39 and 40 respectively, to a point adjacent the forward end of said cutter head, and are secured to the underside thereof and form forward continuations of said walls 39 and 40, to confine the cuttings as they leave the kerf to the path of said cutter chain and deflect them through the opening 31 in the casing 27 to the screw conveyor 30, and to close said cutter chain as it leaves and enters the kerf, so as to keep down the dust caused by cutting.

The portion of the tubular casing 27 inwardly of the helical screw 30 is closed by a bearing support member 44 having a shaft 45 journaled thereon, intermediate its ends, on a ball bearing 46. Said shaft extends within a tubular shaft 47 and has an inner reduced end 49 having a sleeve 50 splined thereon. Said sleeve is suitably secured to the inside of said tubular shaft and forms a means for driving said tubular shaft from said shaft 45. A rod 51 is threaded in the end of said shaft 45 and extends along said tubular shaft to the outer end thereof. A nut 52 serves to lock said rod to said shaft 45 while a nut 53 threaded on the outer end of said shaft abuts the outer

end of a closure member 54 for said tubular shaft, to draw said shaft in tight engagement with said splined sleeve 50 and to secure said tubular shaft to said shaft 45. The blade of the helical screw 5 is suitably secured to the outer side of said tubular shaft and extends therealong, for discharging the cuttings from the open end of said tubular portion of said casing.

The opposite or outer end of the shaft 45 is 10 journaled in an end wall 55 of the casing 27 on a ball bearing 56. A bevel gear 57 is freely mounted on said shaft and has clutch jaws 59 extending from the end of its hub towards the end wall 55. Said jaws are adapted to be engaged by corresponding jaws of a clutch collar 60, which is feathered on said shaft and serves to selectively connect said bevel gear with said shaft. A spring 61 encircles said shaft and abuts said clutch collar to urge said clutch collar into position to engage the jaws 59, 59. A shifting mechanism consisting of a suitable system of links and levers may be provided to operate said clutch. Said shifting mechanism for said clutch may be of any well known form, so need not herein be shown or described in detail.

The tubular portion of the casing 27 is provided with a hinged door 62 at its upper side, to afford access to the screw 30, to permit the removal of undesirable material which may become lodged 30 therein, when necessary. Said door may be interlocked with the mechanism for shifting the clutch collar 60 in a manner similar to that shown and described in Patent No. 2,352,795, which issued to W. T. McCullough on July 4, 1944.

The drive from the sleeve 23 to the bevel gear 57 and the helical screw 30 includes a spur gear 63 which is driven from the supporting and driving sleeve 23 for the cutter chain drive sprocket 21. Said spur gear has a downwardly extending hub portion 64 keyed adjacent the lower end of said sleeve 23 and journaled on its outer periphery in the flanged portion of an annular inwardly flanged plate 65, which is secured to said cutter head (see Figure 5). Said spur gear is of a relatively large diameter and meshes with and drives a spur gear 66 of a smaller diameter than said spur gear 63, which is journaled on a vertical shaft 67 mounted at its ends in the cutter bar support portion 17 of the cutter head 15. A spur gear 69 is formed integrally with said spur gear 66 and is spaced thereabove. Said spur gear is of a larger diameter than said spur gear 66 and meshes with and drives a spur gear 70, journaled on its hub on a vertical shaft 71. Said last mentioned spur gear is of a smaller diameter than said spur gear 69, to drive said vertical shaft at a higher rate of speed than the speed of rotation of said sleeve 23. Said vertical shaft is journaled adjacent its lower end in a bearing support member 73 mounted in the top portion of said casing and projects downwardly therefrom and has a bevel pinion 75 keyed on its lower end, which meshes with the bevel gear 57. Said vertical shaft is journaled at its upper end in a top cap piece 76, which forms a closure member for an upwardly projecting gear housing portion 77 of said casing.

An overload release clutch 78 is provided to drive the vertical shaft 71 from the spur gear 70. Said clutch may be of a well known form and is no part of my present invention, so will not herein be shown or described in detail except to set forth that it includes two engaging members 79 and 80 having meshing modified V-shaped jaws of a relatively low angle of incidence, which are held in engagement with each other by means of a

compression spring 81. Upon overload conditions, as when the helical screw 30 becomes jammed, the member 79 will move out of engagement with the member 80 against the spring 81 until the overload conditions are relieved.

The means for leveling the pile of cuttings discharged by the helical screw 30 and keeping said pile of cuttings down to a predetermined height, includes a reciprocably movable scraper 83. Said scraper is supported in a projecting arm 94 of a frame 84, for reciprocable movement therealong, on a guide shaft 85 mounted in said arm at its ends, and is reciprocably moved along said frame by means of a reversely threaded rotatable screw 86 journaled at its ends in said arm.

The frame 84 also includes an inner housing portion 87 from which the arm 94 extends. Said inner portion of said frame is mounted on an annular flanged portion 88 of an upwardly projecting cylindrical portion 89 of the casing 27, adjacent the discharge end of the tubular portion of said casing. A retaining ring 90, secured to the bottom of said housing portion, abuts the underside of the flange 88 for retaining said frame to said annular flange and permitting pivotal movement of said frame about said annular flange. A central boss 91 coaxial with the pivotal axis of said frame extends downwardly from a top thereof and is pivotally mounted on the upper end of a vertical shaft 93, which is mounted at its lower end in the top of the casing 27. Said arm 94 is herein shown as being hollow and of a substantially oval formation and open at its bottom, to permit the scraper 83 to depend therefrom as it travels therealong.

The scraper 83 is pivotally mounted between two spaced depending lugs 92, 92 of a carrier 95 on a pivotal pin 96. Said carrier is slidably mounted on the guide shaft 85 and has the reversely threaded shaft 86 extending therethrough. Said scraper has a rearwardly projecting engaging end 97, which is adapted to engage the underside of the carrier 95, to hold said scraper in a vertical position during movement of said carrier towards the outer end of said frame, and permit said scraper to pivot upwardly during movement of said carrier and scraper towards the inner end of said frame. A follower 99 is pivotally mounted in said carrier member. Said follower extends inwardly from the outer side of said carrier member and engages the threads of said reversely threaded screw, to cause said carrier and scraper to move along said screw and guide shaft and to reverse its direction of travel when it reaches either end of said shaft, upon rotation of said shaft in one direction, in a manner well known to those skilled in the art.

The inner end of the reversely threaded screw 86 has the hub of a bevel gear 100 freely mounted thereon. Said bevel gear meshes with and is driven from a bevel pinion 101 journaled on the vertical shaft 93. A jaw clutch member 103, which may be operated in a well known manner, is provided to selectively connect said reversely threaded shaft with said bevel gear. The bevel pinion 101 has a spur gear 104 keyed on its hub, which meshes with and is driven from a spur gear 105 freely mounted on a vertical shaft 106, which shaft is mounted at its ends in the cutter bar support portion 17 of the cutter head 15. A spur gear 107 is shown as being formed integrally with the spur gear 105 and as being spaced beneath said spur gear. Said spur gear meshes with and is driven from the spur gear 63.

It may be seen from the foregoing that when

the clutch member 103 is positioned to drive the reversely threaded screw 86 from the bevel gear 100, the scraper 83 will reciprocably move back and forth along the projecting arm 94 to engage and level the top of the pile of cuttings discharged by the helical screw 30. It should here be noted that the bottom of the scraper 83 is spaced a slight distance above the casing 27 and is also a slight distance forwardly of said casing at the end of its path of travel towards the discharge end of the helical screw 30, to cause the discharge end of the casing 27 to be closed by the cuttings so the pile of cuttings will be built up from its inside in a manner which has been clearly shown and described in Patent No. 2,362,837, which is issued to W. T. McCullough on Nov. 14, 1944, to prevent the coal dust from being expelled to the open air. During the leveling operation by said scraper 83, the arm 94 may be angularly moved back and forth about the axis of the vertical shaft 93 under control of the operator, to change the position of said scraper to follow the cuttings discharged by said helical screw, as the cutter bar 19 moves in an arcuate path about the axis of the turntable during cutting. A suitable control rod having a hand grip on its outer end (not shown) may be pivotally connected to the outer end of said arm to permit the operator to move it back and forth at a distance from said frame.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In combination with a kerf-cutting machine adapted to cut along the ground by movement about a vertical axis and having a depending cutter head having a cutter bar projecting therefrom with a cutter chain orbitally movable about said cutter bar, means journaled in said cutter head for driving said cutter chain about said cutter bar including a vertical drive member having a cutter chain drive sprocket mounted thereon, means mounted at the rear end of said cutter head in the path of said cutter chain as it travels about said sprocket for collecting the cuttings cut by said cutter chain including a cuttings discharge conveyor having a casing extending across the rear end of said cutter bar with a screw conveyor element mounted therein, said casing opening towards said cutter chain as it rounds said sprocket in cuttings receiving relation with respect thereto, and means for driving said screw conveyor element from said drive member, including a gear mounted on said drive member and driven thereby, a vertical shaft spaced from said gear and journaled in said casing, a selective bevel gear reduction from said vertical shaft to said screw conveyor element, and a spur gear drive from said gear to said vertical shaft.

2. A cuttings removing device adapted for connection with a kerf-cutting machine of the type adapted to cut a kerf by movement of its cutter bar about a vertical axis comprising a tubular casing having a screw conveyor element mounted therein and adapted to be mounted to the rear of a cutter bar in cuttings receiving relation with respect thereto at the point where the cutter chain reverses its direction of travel, said casing

having an opening cuttings receiving portion in the path of the cutter chain and having a screw conveyor element mounted therein for discharging the cuttings beyond the end of said casing, said casing having opposite arcuate side wall portions extending outwardly and forwardly of said open cuttings receiving portion and conforming to the path of said cutter chain as it reverses its direction of travel, and said arcuate side wall portions with the ground, serving to 10 confine the cuttings to the path of said cutter chain and guide the cuttings into said open cuttings receiving portion of said casing and to keep down the dust caused by cutting.

3. In combination with a kerf-cutting machine having a depending cutter head, a cutter chain carrying cutter bar projecting from said cutter head and adapted to cut a kerf by movement about a vertical axis, cuttings collecting and discharging means mounted at the rear end of said cutter head in cuttings receiving relation with respect to said cutter chain including a casing extending across the rear end of said cutter bar and having a screw conveyor element therein, and means disposed above said screw conveyor element and operable during the cutting operation for leveling off the pile of cuttings discharged by said screw conveyor element, to prevent the overloading of said screw conveyor element that would be caused by building up high piles of cuttings from the bottom of the pile by said screw conveyor element.

4. In combination with a kerf-cutting machine having a depending cutter head, a cutter chain carrying cutter bar projecting from said cutter head and adapted to cut a kerf by movement about a vertical axis, cuttings collecting and discharging means mounted at the rear end of said cutter head in cuttings receiving relation with respect to said cutter chain including a casing extending across the rear end of said cutter bar and having a screw conveyor element therein, and a reciprocating scraper mounted on said cutter head above said screw conveyor in the path of the cuttings discharged thereby, for leveling off the pile of coal discharged by said screw conveyor, to prevent the overloading of said screw conveyor element that would be caused by building up high piles of cuttings from the inside of the pile by said screw conveyor element.

5. In combination with a kerf-cutting machine having a depending cutter head, a cutter chain carrying cutter bar projecting from said cutter head and adapted to cut a kerf by movement about a vertical axis, cuttings collecting and discharging means mounted at the rear end of said cutter head in cuttings receiving relation with respect to said cutter chain including a casing extending across the rear end of said cutter bar and having a screw conveyor element therein, and means disposed above said screw conveyor element and operable during the cutting operation for leveling off the pile of cuttings discharged by said screw conveyor element, to prevent the overloading of said screw conveyor element that would be caused by building up high piles of cuttings from the inside of the pile by said screw conveyor element, including a frame mounted on the upper side of said casing adjacent the discharge end thereof and projecting outwardly therefrom, a scraper element mounted on said frame for movement therewith, and power means for moving said scraper along said frame.

6. In combination with a kerf-cutting machine 75

having a depending cutter head, a cutter chain carrying cutter bar projecting from said cutter head and adapted to cut a kerf by movement about a vertical axis, cuttings collecting and discharging means mounted at the rear end of said cutter head in cuttings receiving relation with respect to said cutter chain including a casing extending across the rear end of said cutter bar and having a screw conveyor element therein, and means disposed above said screw conveyor element and operable during the cutting operation for leveling off the pile of cuttings discharged by said screw conveyor element, to prevent the overloading of said screw conveyor element that would be caused by building up high piles of cuttings from the inside of the pile by said screw conveyor element, including a frame mounted on the upper side of said casing adjacent the discharge end thereof and having an arm projecting outwardly therefrom, a scraper element mounted on said arm for movement therewith and disposed above the discharge end of said screw conveyor, and power means for moving said scraper along said arm including a power driven screw journaled in and extending along said arm, and an operative connection from said screw to said scraper.

7. In combination with a kerf-cutting machine having a depending cutter head, a cutter chain carrying cutter bar projecting from said cutter head and adapted to cut a kerf by movement about a vertical axis, cuttings collecting and discharging means mounted at the rear end of said cutter head in cuttings receiving relation with respect to said cutter chain including a casing extending across the rear end of said cutter bar and having a screw conveyor element therein, and means disposed above said screw conveyor element and operable during the cutting operation for leveling off the pile of cuttings discharged by said screw conveyor element, to prevent the overloading of said screw conveyor element that would be caused by building up high piles of cuttings from the inside of the pile by said screw conveyor element, including a frame mounted on the top of said casing adjacent the discharge end thereof for adjustable movement about a vertical axis and having an arm projecting outwardly therefrom in the path of the cuttings discharged by said screw conveyor element, a scraper element depending from said arm and mounted thereon for movement therewith and having a lower edge movable in a plane disposed a slight distance above the discharge end of said screw conveyor element, and a power driven reversely threaded screw for reciprocably moving said scraper along said arm.

8. In combination with a kerf-cutting machine adapted to cut along the ground by movement about a vertical axis and having a depending cutter head, a cutter bar projecting from said cutter head, a cutter chain movable about said cutter bar, a drive member and sprocket journaled in said cutter head for driving said cutter chain about said cutter bar, a screw conveyor mounted at the rear end of said cutter head in cuttings receiving relation with respect to said cutter chain for collecting the cuttings discharged by said cutter chain and discharging them to the retreating side of said cutter chain, a scraper mounted on said cutter head above said screw conveyor for reciprocable movement towards and from said cutter head in the path of the cuttings discharged by said screw conveyor, for leveling the pile of cuttings discharged by said screw con-

veyor, and a drive connection from said drive member for said sprocket to said scraper, for reciprocably driving said scraper towards and from said cutter head.

9. In combination with a kerf-cutting machine adapted to cut along the ground by movement about a vertical axis and having a depending cutter head, a cutter bar projecting from said cutter head, a cutter chain movable about said cutter bar, a drive member and sprocket journaled in said cutter head for driving said cutter chain about said cutter bar, a screw conveyor mounted at the rear end of said cutter head in cuttings receiving relation with respect to said cutter chain for collecting the cuttings discharged by said cutter chain and discharging them to the retreating side of said cutter chain, power means operable during the cutting operation for leveling off the pile formed by said screw conveyor, to prevent the overloading of said screw conveyor that would be caused by building up high piles of cuttings from the inside of the pile by said screw conveyor, including a frame mounted on said cutter head and having an arm projecting therefrom in the path of the cuttings discharged by said screw conveyor and adjustably movable about a vertical axis, a scraper depending from and mounted on said arm for reciprocable move-

ment therealong, but having a bottom scraping surface movable in a plane disposed a slight distance above said screw conveyor, a reversely threaded feed screw journaled in said arm and operatively connected with said scraper, for reciprocably moving said scraper along said frame upon rotation of said screw in one direction, and a selective drive connection from said drive member for said sprocket to said feed screw, for rotatably driving said screw.
